CORING DEVICE

Everett E. Rigney, Modesto, Calif.

Application October 22, 1946, Serial No. 704,859

10 Claims. (Cl. 146—52)

1

This invention relates generally to food machinery.

In particular the invention is directed to, and it is an object to provide, a power-actuated device for coring fresh bell peppers or the like preparatory to processing thereof.

Another object of the invention is to provide a coring device, for the purpose described, which includes, in novel assembly, a driven coring unit, and a holding assembly operative to clampingly engage a bell pepper or the like and to then reciprocate in a direction to advance the pepper to and from the coring unit whereby the core is effectively cut away from the remainder of the pepper.

A further object is to provide a coring device, as in the preceding paragraph, in which the holding assembly includes a pair of spaced plates mounted for movement, one toward the other, to clampingly engage a pepper therebetween, and then both moved toward the coring unit for coring of the clamped pepper; said other plate having an opening therein to permit entry of the coring unit into the pepper from one end thereof.

An additional object is to apply novel semi-automatic safety means to the device to prevent accidental engagement of the operator's hands with the driven coring unit during use of the device.

A further object of the invention is to provide a practical coring device, and one which will be exceedingly effective for the purpose for which it is designed.

These objects are accomplished by means of such structure and relative arrangement of parts as will fully appear by a perusal of the following specification and claims.

In the drawings:

Fig. 1 is a front elevation of the device showing the parts in starting position.

Fig. 2 is a fragmentary front elevation of the device showing the position of the parts upon initial depression of the hand lever, with resultant raising of the shield.

Fig. 3 is a similar view, but shows the position of the parts with the hand lever fully depressed, and the pepper holding assembly lowered into engagement with the coring unit.

Fig. 4 is a longitudinal sectional elevation of the device.

Fig. 5 is a fragmentary plan view on line 5—5 of Fig. 1.

Fig. 6 is a fragmentary plan view on line 6—6 of Fig. 2.

Referring now more particularly to the characters of reference on the drawings, the device comprises an upstanding open frame, indicated generally at 1, and including a top cross beam 2, end posts 3, and vertically spaced cross beams 4 and 5 intermediate the top and bottom of said frame.

Between the posts 3 the device is provided with a vertical spindle 6 driven from adjacent its lower end by means of an endless drive 7; the spindle being carried in bearings 8 on the cross beams 4 and 5, and said spindle terminating directly above the cross beam 4 and there being fitted with a rotary coring unit 9. The coring unit 9 includes a head 10 and upstanding blades 11.

In position normally above the rotary coring unit 9 the device incorporates a pepper holding assembly, indicated generally at 12, which comprises the following:

A horizontal bottom plate 13 extends transversely of the device and is carried at one end on the upper end of a vertical slide bar 14 journaled for sliding movement in the frame 1 through bearings 15. A stop collar 16 on the slide bar 14 limits upward movement thereof to the position shown in Fig. 1. The horizontal bottom plate 13 is normally urged in an upward direction, and to the limit of its movement, by a pair of relatively light-weight suspension springs 17 attached to opposite end portions of the plate 13 and the top cross beam 2. The bottom plate 13 is formed with a central opening 18 directly above the rotary coring unit 9, and of a diameter so that such unit may pass upwardly therethrough.

Above and in symmetrical relation to the bottom plate 13 the pepper holding assembly 12 includes a horizontal, transversely extending top plate 19, secured at one end in connection with a vertical slide bar 20 slidably guided in bearings 21 on the side frame 1 opposite the slide bar 14.

A stop collar 22 limits upward movement of the top plate 19 to the position shown in Fig. 1; the slide bar 20, together with said top plate 19, normally being urged upwardly to the limit of its movement by means of a suspension spring 23 connected between the upper end of the slide bar 20 and the top of a tubular housing 24 into which said slide bar projects.

Guide rods 25 are fixed on the bottom plate 13, adjacent its ends, and extend in slidable relation through the top plate 19; a nut 26 being threaded on the upper end of one of said guide rods so as to

assure of lifting of the bottom plate 13 to its normal or starting position when the top plate 19 rises to its starting position, as shown in Fig. 1. In this starting position the plates 13 and 19 are spaced apart sufficiently for the entry of a pepper 27 therebetween, with the stem end of said pepper directly over the opening 18, and with the opposite end of the pepper directly below small teeth 28 on the under side of the top plate 19.

A longitudinal hand lever 29 extends along one side of the machine and projects through a vertical slot 30 in the lower end portion of the slide bar 20; said lever being fitted at its forward end, and in front of the device, with a hand plate 31. A return spring 32 normally maintains the lever 29 in the top or upper end of the slot 30.

In front of the slide bar 20 the hand lever 29 passes through a depending slotted cam lever 33 which is formed as one leg of a bellcrank 34 pivoted, as at 35, for swinging movement in a vertical transverse plane. The other leg of the bellcrank lever 34 is fitted with a shield 36, normally disposed mainly below the bottom plate 13, whereby a pepper 27 can be placed on said bottom plate 13 without obstruction.

Upon initial depression of the hand lever 29, it moves downwardly in the slot 30, and first swings the slotted cam lever 33 laterally inwardly, raising the shield 36.

Thereafter with continued downward movement of the hand lever 29 it engages the bottom of slot 30 and shifts the slide bar 20 downwardly. When this occurs the top plate 19 is moved downwardly into engagement with the pepper 27, and thence with continued downward movement of said top plate, the latter, together with the bottom plate 13, and the pepper then clamped therebetween, move downwardly in unitary relation until the rotary coring unit 9 passes through the opening 19 to effect a coring operation within said pepper.

Upon release of the hand lever 29 the several springs return the parts to their starting position, whereupon the cored pepper 27 is removed and the next one disposed in position for the coring operation.

As a protective measure a swinging guard 37 is pivotally mounted, as at 38, in connection with the bottom plate 13 on the under side thereof, and normally covers, as in Fig. 5, the opening 18 to prevent the operator's fingers from slipping therethrough into engagement with the rotary coring unit 9. The swinging guard 37 includes a projecting trigger 39 engaged by the bellcrank lever 34 when the shield 36 is swung to raised position, whereby to swing said guard clear of the opening 18, as in Fig. 6, and to permit of passage of the rotary coring unit 9 through said opening. The swinging guard 37 is returned to starting position by a spring 40 when the shield 36 lowers, and said swinging guard is maintained in working contact with the bottom plate 13 by a hold-down guide 41.

With the described device, an operator seated in front thereof can rapidly, effectively, and with safety, core bellpeppers with a minimum of handling thereof; the machine being simple in its structural arrangement, and designed so that it requires a minimum of maintenance and repair.

From the foregoing description it will be readily seen that there has been produced such a device as substantially fulfills the objects of the invention as set forth herein.

While this specification sets forth in detail the present and preferred construction of the device, still in practice such deviations from such detail

may be resorted to as do not form a departure from the spirit of the invention, as defined by the appended claims.

Having thus described the invention, the following is claimed as new and useful, and upon which Letters Patent are desired:

1. A coring device for vegetables or the like comprising a frame, a rotary coring unit journaled in the frame for rotation about an upstanding axis, a holding assembly adapted to support a vegetable initially spaced above and aligned with the coring unit, the assembly including vertically spaced plates mounted in the frame for independent vertical motion, and means operative to move the upper plate downward to first engage a vegetable seated on the lower plate and to then move both plates downward, the lower plate having an opening over which the vegetable is seated and the coring unit working through said opening upon downward movement of said assembly.

2. A coring device for vegetables or the like comprising a frame, a rotary coring unit journaled in the frame for rotation about an upstanding axis, a holding assembly adapted to support a vegetable initially spaced above and aligned with the coring unit, the assembly including vertically spaced plates mounted in the frame for independent vertical motion, and means operative to move the upper plate downward to first engage a vegetable seated on the lower plate and to then move both plates downward, the lower plate having an opening over which the vegetable is seated and the coring unit working through said opening upon downward movement of said assembly.

25 3. A coring device for vegetables or the like comprising a frame, a rotary coring unit journaled in the frame for rotation about an upstanding axis, a holding assembly adapted to support a vegetable initially spaced above and aligned with the coring unit, the assembly including vertically spaced plates mounted in the frame for independent vertical motion, and means operative to move the upper plate downward to first engage a vegetable seated on the lower plate and to then move both plates downward, the lower plate having an opening over which the vegetable is seated and the coring unit working through said opening upon downward movement of said assembly; both plates being spring suspended in the frame.

30 4. A coring device for vegetables or the like comprising a frame, a rotary coring unit journaled in the frame for rotation about an upstanding axis, a holding assembly including a cutting head on its outer end, a pair of plates slidably mounted in the frame, yieldable means normally maintaining one of said plates spaced from said cutting head, yieldable means normally maintaining the other plate spaced from said one plate, said one plate having an opening in alignment with the cutting head, and lever means connected with said other plate and operable to urge said other plate toward said one plate whereby a vegetable disposed between the plates together with said one plate will be moved to project said cutting head through said opening and into said vegetable in coring relation to the latter.

45 5. A coring device for vegetables or the like comprising a frame, a rotary coring unit mounted for rotation about an axis, said coring unit including a cutting head on its outer end, a pair of parallel guide bars slidably mounted in the frame, a plate on each guide bar, said plates being disposed in substantial parallelism with each other, yieldable means normally maintaining one of said plates spaced from said cutting head, yieldable means normally maintaining the other plate spaced from said one plate, said one plate having an opening in alignment with said cutting head, and lever means connected with the guide bar of said other plate and operable to slide the same to move said other plate toward said one plate whereby a vegetable disposed between the plates together with said one plate will be moved to project the cutting head through said opening.

60 6. A coring device for vegetables or the like comprising a frame, a rotary coring unit mounted for rotation about an axis, said coring unit including a cutting head on its outer end, a pair of parallel guide bars slidably mounted in the frame, a plate on each guide bar, said plates being disposed in substantial parallelism with each other, yieldable means normally maintaining one of said plates spaced from said cutting head, yieldable means normally maintaining the other plate spaced from said one plate, said one plate having an opening in alignment with said cutting head, and lever means connected with the guide bar of said other plate and operable to slide the same to move said other plate toward said one plate whereby a vegetable disposed between the plates together with said one plate will be moved to project the cutting head through said opening.

and into such vegetable in coring relation to the latter.

6. A coring device for vegetables or the like comprising a frame, a rotary coring unit mounted for rotation about an axis, said coring unit including a cutting head on its outer end, a pair of parallel guide bars slidably mounted in the frame, a plate on each guide bar, said plates being disposed in substantial parallelism with each other, yieldable means normally maintaining one of said plates spaced from said cutting head, yieldable means normally maintaining the other plate spaced from said one plate, said one plate having an opening in alignment with said cutting head, and a lever pivoted on the frame and engageable with the guide bar on the said other plate to slide said bar and move said other plate toward said one plate, whereby a vegetable disposed between said plates together with said one plate will be moved to project the cutting head through said opening and into such vegetable in coring relation to the latter.

7. A structure as in claim 3 including a guard plate normally closing said opening and means interposed between said lever means and the guard plate and operable to swing such plate clear of the opening prior to the projection of the cutting head through said opening.

8. A structure as in claim 3 including a shield normally disposed clear of the said one plate, means connecting said shield with said lever means and operable to move the shield across the outer edge of the said one plate and toward the other plate prior to the movement of the plates.

9. A structure as in claim 3 including a guard plate pivoted to said one plate and normally covering the opening therein, a finger on said guard plate projecting beyond one edge of said one plate, a bell crank pivoted to the frame, a shield

fixed to one leg of the bell crank and normally positioned clear of said one edge of such one plate, means connected between said bell crank and said lever means to turn the bell crank on its pivot and swing the shield across the said edge of the said one plate prior to the movement of the plates, the edge of the shield being engageable with the finger to simultaneously swing the guard plate clear of the opening with the movement of the shield.

10. A structure as in claim 6 including a bell crank pivoted to the frame, a shield fixed to one leg of the bell crank and normally lying adjacent one edge of said one plate but below the surface of such plate, the other leg of the bell crank being in the form of a slotted cam lever, the said first named lever projecting through said cam lever and operable to turn the bell crank on its pivot and swing the shield across the edge of said one plate prior to the movement of the plates.

EVERETT E. RIGNEY.
